UNITED STATES PATENT OFFICE.

ROBERT C. HUFFMAN, OF BALTIMORE, MARYLAND.

CONCRETE-HEATING MACHINE.

No. 853,456.

Specification of Letters Patent.

Patented May 14, 1907.

Application filed February 19, 1907. Serial No. 358,161.

To all whom it may concern:

Be it known that I, ROBERT C. HUFFMAN, a citizen of the United States, residing at Baltimore city, State of Maryland, have invented certain new and useful Improvements in Concrete-Heating Machines, of which the following is a specification.

My invention relates to an improvement in concrete heating machines, the object being to provide a machine for heating concrete in cold weather.

It is a well known fact that concrete cannot be successfully mixed in a temperature below 32° Fr. on account of its tendency to freeze, and when frozen it loses its strength and utility.

To prevent the freezing of concrete while in the course of being mixed, I have invented this device, thus making it possible to mix concrete in cold weather at a temperature of below 32°, without its becoming deteriorated.

The device is particularly adapted to be used in the mixing of concrete in the construction of bridges, tunnels and the like where the mixing is necessarily or ordinarily exposed to a cold temperature, and whereby for the reasons stated cannot be successfully accomplished when the temperature is below 32°. In the construction of bridges, tunnels and the like as well as in any and all other construction where concrete is used, the loss of time incurred by reason of cold weather, wherein the concrete cannot be mixed, is often the cause of financial loss. To obviate to a great extent such delays from the cause stated and to prevent such financial loss as is ordinarily incurred, thereby I have invented and constructed this device.

My invention consists in certain new and novel features of construction and combination of parts, which will be hereinafter described and pointed out in the claims.

Referring to the accompanying drawings in which like letters and figures of reference indicate corresponding parts in each of the several views. Figure 1, is a side elevation, showing the position of the device when the contents is discharged. Fig. 2, is an end view showing the cover raised; Fig. 3, is a top plan view with the cover removed. Fig. 4, is a side elevation showing the cover raised; Fig. 5, is an end view with that part of the body portion removed.

A is a longitudinal box or body part; 1 is a base or stand; 2 is a supply pipe; 3 is a trunnion into which the feed pipe is extended and 55 2 is a cap secured on the end of the supply pipe 2; 4 are clamps which secure the body portion A to the trunnion 3, which trunnion is pivotally secured to the base or stand at 5; 60 6 is a cover hinged to the top part of the body portion by the hinges 7; the body part A is provided with a door 8 in the rear end thereof, which door is hinged to the top end portion of the body part A at 9; secured on the 65 top rear end of the body part A by means of screws 10 is a cover stop 11; 12 and 13 are valves secured in the pipes 14 and 15; 16 and 17 are ells, the pipe 14 is vertically extended by the use of the ell 16 and the pipe 15 is ex- 70 tended transversely under the body portion near the front end to the center thereof by use of the ell 17; 18 is an ordinary staple secured to the end of the hook 19, which hook engages with the end of the body part A, by 75 any suitable means to prevent the body part from being tilted beyond a desired angle.

The pipe 14 is secured to the supply pipe 2 by means of the swivel T fitting 20 and is longitudinally extended to the rear end of the 80 body part A, where by the use of an ell 16 it is vertically extended to the top of the body part, secured on the end thereof is a ball and socket joint 21, whereby the pipe is extended horizontally across the top end portion of the 85 body part A. Secured to the horizontal portion of the pipe 14 by means of the union joints 22 are a series of longitudinal arranged pipes 23, which are secured to the cover 6, by means of the clamps 24; these pipes are slot- 90 ted at suitable distances as indicated by 25, the free end of the pipes being closed by means of the caps 26; the pipe 15 is similarly secured on the supply pipe 2 by means of a similar T fitting 27; on the opposite end of 95 the pipe 15 is secured an ell 17, by reason of which the pipe 15 is extended transversely across the front end of the body part A to the center thereof, on the end of the said transverse extension of the said pipe 15 is secured 100 another ell 28, whereby the said pipe is continued vertically and joined to a T fitting 29. The said T fitting is connected with a series of short sections of pipe 30; additional T fittings 31 are used to connect a series of longitudinal pipe sections 32 extending and ly- 105

ing in the bottom of the body part A, and are similarly slotted as are those secured to the top cover which are similarly designated 25, (as shown in Fig. 3); the free ends of these 5 pipes are closed by means of caps (not shown) but similar to those designated 26 of the cover; by the use of additional ell fittings 33 and T fittings 34, a series of pipes 35 are constructed transversely across the front end as 10 are also a series of pipes longitudinally constructed within the sides of the body part A, as indicated by 36 as shown in Fig. 4, and are secured to the inner side walls of the body part A by similar clamps 24 as are those of 15 the cover which are similarly designated; the free ends of these pipes are closed by means of the caps 37. These pipes as well as those extended transversely across the end are similarly slotted as are those of the cover in 20 the bottom of the body part and which slots are similarly designated 25, the object of which will be hereinafter explained.

My invention is operative as follows: The proportionate equalities of broken stone, 25 sand and cement are placed in the body part A, which is then closed by means of the cover 6; live steam is then discharged through the supply pipe 2, and by reason of the valves 12 and 13 this discharge is regulated. Steam 30 entering through supply pipe 2 passes through pipe 14 and through ball and socket joint 21 to the extension of pipe 14 leading to the series of pipes secured to the cover and by reason of the slots 25 in the said pipes, live 35 steam is discharged therethrough and into the body part. Steam entering through supply pipe 2 passes through pipe 15, which connects with the series of pipes 35 located in the front end of the body part A, and by reason 40 of the connections with these pipes as has already been explained, the steam passes into the series of longitudinal pipes 32 secured within the bottom part A, and in a similar manner, and by the use of similar connections and fittings, the pipes 36 secured to 45 the inner side walls are connected with the pipes 35 and through which and by reason of the said connections, live steam is discharged therein, and through the slots 23, as is the 50 case with all the other pipes; by reason of discharging live steam into the body part in the manner described, the contents become thoroughly heated and partially mixed and the steam condensing therein, supply the 55 water necessary to the mixing of the concrete and stone becoming heated retains sufficient heat to permit the further mixing of the concrete in a temperature which without the use of my device would be prohibitive for 60 the reasons previously given.

Slight changes might be resorted to in the form and arrangement of the several parts

described, without departing from the spirit and scope of my invention, hence I do not desire to limit myself to the exact construction as herein set forth, but;

Having described my invention, what I claim as new and desire to secure by Letters Patent, is:

1. A concrete heating machine, comprising a longitudinal body part, of a base, a trunnion pivotally secured to the base, means for securing the body part to the trunnion, a supply pipe, an additional pipe leading from the said supply pipe, longitudinal 70 extended pipes provided with slots cut therein and secured within the said body part on the bottom thereof, means for connecting the said longitudinal extended pipes with the said pipe leading from the said supply pipe and a valve on the said pipe for controlling the discharge of steam there-through, substantially as described.

2. A concrete heating machine, comprising a longitudinal body part, of a base, a 85 trunnion pivotally secured to the base, means for securing the body part to the trunnion, a supply pipe, an additional pipe leading from the said supply pipe, pipes longitudinally extended and provided with 90 slots cut therein in the bottom part of the said body part, similar pipes extending transversely across the end portion of the said body part, means for connecting the said pipe longitudinally extended in the 95 bottom part with those transversely extended across the end portion, similar pipes longitudinally extended and secured to the inner side walls of the said body part, means for connecting the said pipes with those 100 transversely extended across the end portion, means for connecting the said pipe leading from the said supply pipe with those transversely extended across the end portion and means on the said pipe leading from 105 the said supply pipe for regulating the discharge of steam therethrough, substantially as described.

3. A concrete heating machine, comprising a longitudinal body part and provided 110 with a cover hinged thereto, a base, a trunnion pivotally secured to the base, means for securing the body part to the trunnion, a supply pipe, slotted pipes longitudinally 115 extended and secured to the inner side of the said cover, a pipe extended longitudinally along the lower side of the body part and connected with the said supply pipe, means on the free end of the said pipe for continuing the same vertically, a hinge joint on the 120 free end of the said vertical extension for extending the said pipe transversely across the top of the said body part near the end portion thereof and means for connecting

the said transverse extension with the longitudinal slotted pipes secured to the inner side of the cover, a steam valve secured on the said longitudinal pipe leading from 5 the supply pipe for regulating the discharge of steam therethrough, substantially as described.

In testimony whereof I affix my signature in presence of two witnesses.

ROBERT C. HUFFMAN.
